UNITED STATES PATENT OFFICE

THOMAS W. BEHAN, OF BINGHAMTON, NEW YORK, ASSIGNOR TO NINETEEN HUNDRED CORPORATION, OF BINGHAMTON, NEW YORK, A CORPORATION OF NEW YORK

DESIGN FOR A COMBINED WASHING MACHINE CASING AND DRIER

Application filed August 5, 1931. Serial No. 40,785. Term of patent 14 years.

To all whom it may concern:

Be it known that I, THOMAS W. BEHAN, a citizen of the United States, residing at Binghamton, in the county of Broome and State of New York, have invented a new, original, and ornamental Design for Combined Washing Machine Casing and Drier, of which the following is a specification, reference being had to the accompanying drawing forming a part thereof.

Figure 1 is a side elevation of a combined washing machine casing and drier embodying my new design,

Figure 2 is an end elevation thereof, and Figure 3 is a perspective view thereof. The opposite side and end present substantially the same appearance as the side and end shown.

I claim:

The ornamental design for a combined washing machine casing and drier as shown and described.

THOMAS W. BEHAN.
